UNITED STATES PATENT OFFICE

139,237

DESIGN FOR A MOBILE SOUND PROJECTOR

William C. Eaves, Elyria, Ohio, assignor to Eaves Sound Projectors, Inc., Dover, Del., a corporation of Delaware

Application October 14, 1943, Serial No. 111,357

Term of patent 14 years

(Cl. D14—3)

To all whom it may concern:

Be it known that I, William C. Eaves, a citizen of the United States of America, residing at Elyria, in the county of Lorain and State of Ohio, have invented a new, original, and ornamental Design for a Mobile Sound Projector, of which the following is a specification, reference being had to the accompanying drawings, forming a part thereof, wherein:

Fig. 1 is a side view of a mobile sound projector embodying my new design;

Fig. 2 is a front view of the mobile sound projector; and

Fig. 3 is a perspective view showing the rear and the other side of the mobile sound projector and with the horn thereof in elevated position.

I claim:

The ornamental design for a mobile sound projector, as shown.

WM. C. EAVES.
